UNITED STATES PATENT OFFICE

WILLIAM A. SMITH, SR., OF EASTON, PENNSYLVANIA, ASSIGNOR TO INGERSOLL-RAND COMPANY, OF JERSEY CITY, NEW JERSEY, A CORPORATION OF NEW JERSEY

VALVE FOR ROCK DRILLS

Application filed November 11, 1930. Serial No. 494,850.

This invention relates to rock drills, but more particularly to a valve for fluid actuated rock drills of the hammer type.

One object of the invention is to obtain a rapid and efficient distribution of the pressure fluid to the cylinder and consequently a rapid action of the hammer piston of the drill.

Another object is to suitably apportion the flow of pressure fluid to the ends of the cylinder so that a greater charge may be admitted to one end of the cylinder than to the other end within a given period of time.

Other objects will be in part obvious and in part pointed out hereinafter.

In the drawings accompanying this specification and in which similar reference characters refer to similar parts,

Figure 1 is a sectional elevation of a rock drill constructed in accordance with the practice of the invention and showing the valve and the piston in certain limiting positions, and

Figure 2 is a view similar to Figure 1 showing the valve and the piston in other limiting positions.

Referring more particularly to the drawings, A designates generally a rock drill comprising a cylinder B having a piston chamber C to accommodate a reciprocatory hammer piston D.

A closure is provided for the front end of the piston chamber C in the form of a bushing E which is suitably bored to act as a guide for a stem F of the piston D and whereby the blows of the piston are delivered to a working implement, only the shank G of which is shown. The bushing E may, as shown, also serve to centralize a front head H with respect to the cylinder B.

In the front head is arranged suitable chuck mechanism designated generally by J to serve as a guide for the working implement and also to transmit rotary movement of the piston D to the working implement, it being understood that the extension or stem F of the piston is slidably interlocked with the chuck mechanism in a well known manner.

In the rear end of the cylinder B is an enlarged bore K and into the rearward end of the bore extends a flange L of a back head O.

The back head O forms a closure for the rear end of the cylinder and, in the present instance, also acts as a housing for a throttle valve P which may be of the rotary type and has a central port Q into which pressure fluid may be constantly introduced from a source of supply (not shown).

In the wall of the throttle valve is a port R which is adapted to register with a passage S in the back head O and which passage opens into a supply reservoir T in the form of an annular groove in the inner or front end of the back head O.

The back head O may be secured in the proper assembled position in any suitable manner, as for instance, by the usual side bolts (not shown) and which side bolts may also serve as a means for clamping the front head H to the cylinder.

Disposed within the bore K adjacent the rear end of the piston chamber C for which it forms a closure is a valve chest comprising in this instance a block U arranged adjacent the rear end of the piston chamber C and a plate V seated upon the rear end of the block. The plate V in turn acts as a seat for a ratchet ring W which is interposed between the plate V and the back head O.

The ratchet ring W is shown provided with the usual introverted teeth X to act as abutments for pawls Y carried by the head Z of a fluted rifle bar b wherewith the piston D is slidably interlocked. The rifle bar b thus extends through the valve chest, and in the present instance a bushing c is disposed in the block U and the plate V to act as a renewable bearing surface for that portion of the rifle bar b which lies within the confines of the valve chest and also to prevent the leakage of pressure fluid along the rifle bar into the piston chamber.

The parts comprising the valve chest are bored to form a valve chamber d for the accommodation of a distributing valve e shown in this instance as being of the reciprocatory type and having a central bore f through which the bushing c extends. The valve e is provided with an intermediate flange g which controls the outlet opening or port h.

of a supply passage *j* leading from the supply reservoir *T* to the valve chamber *d*.

On the front end of the valve *e* is a head *k* of somewhat smaller diameter than the flange *g* and the forward end or surface *o* of which constitutes a pressure surface which lies within a pressure chamber *p* in the front end of the valve chamber *d*. Similarly, on the rear end of the valve *e* is a head *q* the rear end *r* of which lies within a pressure chamber *s* and constitutes a pressure surface against which pressure fluid may act for actuating the valve. The head *q* in this instance is of smaller diameter than the head *k* and therefore of smaller diameter than the flange *g*.

The pressure fluid utilized for actuating the valve *e* is conveyed from the piston chamber *C* to the pressure chambers *p* and *s*. To this end the cylinder is provided with kicker passages *t* and *u*. The kicker passage *t* opens with one end into the cylinder at a point forwardly of the transverse median line of the piston chamber *C* and communicates with its opposite end with the pressure chamber *p*. The kicker passage *u* leads from the piston chamber *C* at a point rearwardly of the transverse median line of said piston chamber and opens with its opposite end into the pressure chamber *s*.

The kicker passages *t* and *u* are provided with atmospheric vents *v* and *w* respectively of smaller cross sectional area than the kicker ports. With the kicker passages and the vents thus proportioned a full supply of pressure fluid may be introduced into the pressure chambers *p* and *s* for actuating the valve *e* from one limiting position to the other and at the same time an immediate outlet is provided for the pressure fluid in the pressure chambers *p* and *s* after the valve is thrown.

The pressure fluid utilized for actuating the piston *D* is conveyed into the rear end of the piston chamber *C* by a rear inlet passage *x* which is preferably located in the block *U* and opens into the valve chamber *d* at a point immediately forwardly of the outlet opening *h* of the supply passage *j*, and pressure fluid is conveyed to the front end of the piston chamber *C* by a front inlet passage *y* which opens into the valve chamber *d* at a point immediately rearwardly of the port *h*. The inlet passages *x* and *y* also serve as exhaust passages for conveying exhaust fluid from the piston chamber to the valve chamber and in the valve chest and in the portion of the cylinder adjacent thereto is an exhaust port *B'* through which exhaust fluid may pass to the atmosphere.

To the end that the charges of pressure fluid to the ends of the piston chamber *C* may be suitably apportioned so that a greater charge will be delivered to the rear end of the piston chamber for driving the piston *D* on its working stroke than will be admitted

to the front end of the piston chamber for lifting or retracting the piston *D*, the flange *g* is provided on its front and rear ends with annular recesses *z* and *2* respectively, thus leaving an intermediate raised or stepped portion *3* in slidable engagement with the wall of the valve chamber *d*.

In order to assure this greater charge of pressure fluid to the rear end of the piston chamber *C* the annular recess *z* which controls the flow of pressure fluid from the supply passage *j* to the inlet passage *x* is of greater depth than the annular recess *2*. As a result of this arrangement, when the valve is in position for admitting pressure fluid into the rear end of the piston chamber *C* a greater flow area will exist around the flange *g* for the passage of pressure fluid to the inlet passage *x* than when the valve is in its opposite limiting position and in which case of course the pressure fluid flows from the supply passage *j* through the flow area formed by the annular recess *2*.

The rear and front ends of the flange *g*, or more particularly, those areas of these portions of the flange *g* which are in excess of the diameters of the heads *k* and *q*, constitute holding surfaces *4* and *5* respectively against which pressure fluid flowing from the supply passage *j* to the inlet passage acts to hold the valve *e* in its limiting positions.

The operation of the device is as follows: With the valve *e* in the position illustrated in Figure 1 and which position the raised portion *3* of the flange *g* lies rearwardly of the port *h* as shown, pressure fluid flows through the valve chamber and the inlet passage *x* into the rear end of the piston chamber *C* to drive the piston *D* forwardly against the working implement. As the piston *D* proceeds in the forward direction it will uncover the kicker passage *u* and admit pressure fluid through the said kicker passage *u* into the pressure chamber *s* where it will act against the pressure surface *r* and throw the valve forwardly.

This movement of the valve may be readily effected since then the pressure chamber *p* will be open to the atmosphere through the passage *t* and the vent *v* and only the pressure fluid flowing across the holding surface *5* will resist movement of the valve. During the admission of pressure fluid into the rear end of the piston chamber *C* a large charge will be admitted thereinto within the slight period of time during which the valve *e* occupies its rearmost position. This is due to the comparatively large flow area provided by the annular recess *z*.

Upon the shifting of the valve *e* to its new position the pressure fluid utilized for throwing it forwardly will immediately escape from the pressure chamber *s* through the kicker passage *u* and the atmospheric vent *w*. This will occur immediately after the

valve has been thrown and the valve will then be held in its forward position only by the pressure fluid acting against the holding surface 4. Meanwhile pressure fluid will flow 5 from the supply port h through the annular recess 2, the valve chamber d and through the inlet passage y into the front end of the piston chamber. Such pressure fluid will act to raise the piston to its initial position.

10 After the piston D has moved rearwardly throughout a portion of its stroke it will uncover the kicker passage t . Pressure fluid will then flow into the pressure chamber p and, acting against the pressure surface o , 15 will actuate the valve e to its initial position.

The pressure fluid previously admitted into the pressure chamber p will then immediately escape through the kicker passage and the atmospheric vent v so that at a proper period 20 in the cycle of operations the valve e may again be thrown forwardly and which movement will only be opposed by the pressure acting against the front holding surface 5.

While the valve e is still in its rearmost 25 position the pressure fluid utilized for actuating the piston D rearwardly will escape through the inlet passage y and the valve chamber d and through the exhaust port B' to the atmosphere. Similarly, upon completion 30 of the forward stroke of the piston and immediately after the valve e has been thrown into the position for retracting the piston the pressure fluid utilized for actuating the piston D on its working stroke will escape 35 from the piston chamber C through the inlet passage x , the valve chamber d and through the exhaust port B' to the atmosphere.

I claim:

1. In a fluid actuated rock drill, the combination of a cylinder and a hammer piston therein, a valve chest having a valve chamber and a supply passage, inlet passages leading from the valve chamber to the cylinder, a valve in the valve chamber having a flange 40 to control the flow of pressure fluid from the supply passage to the inlet passages, opposed pressure surfaces on the valve against which pressure fluid acts for throwing the valve, holding areas on the valve intermittently exposed to pressure fluid for holding the valve in the limiting positions, and means on the flange cooperating with the valve chest to assure a greater area of communication between the supply passage and one inlet passage 45 sage than between the supply passage and the other inlet passage.

2. In a fluid actuated rock drill, the combination of a cylinder and a hammer piston therein, a valve chest having a valve chamber 50 and a supply passage, inlet passages leading from the valve chamber to the cylinder, a valve in the valve chamber having a flange to control the flow of pressure fluid from the supply passage to the inlet passages, opposed pressure surfaces on the valve against 55

which pressure fluid acts for throwing the valve, holding areas on the valve intermittently exposed to pressure fluid for holding the valve in the limiting positions, and recesses on the flange through which pressure 70 fluid flows and being of different areas to assure a greater flow of pressure fluid from the supply passage to one inlet passage than to the other inlet passage.

3. In a fluid actuated rock drill, the combination of a cylinder and a hammer piston therein, a valve chest having a valve chamber and a supply passage, inlet passages leading from the valve chamber to the cylinder, a valve in the valve chamber having a flange to control the flow of pressure fluid from the supply passage to the inlet passages, opposed differential pressure surfaces on the valve against which pressure fluid acts for throwing the valve, holding areas on the valve intermittently exposed to pressure fluid for holding the valve in the limiting 85 positions, and control means on the valve for effecting a greater flow of pressure fluid from the supply passage to one inlet passage than 90 to the other inlet passage.

4. In a fluid actuated rock drill, the combination of a cylinder and a hammer piston therein, a valve chest having a valve chamber and a supply passage, inlet passages leading from the valve chamber to the cylinder, a valve in the valve chamber having a flange to control the flow of pressure fluid from the supply passage to the inlet passages, control means on the flange for effecting a greater flow of pressure fluid from the supply passage to one inlet passage than to the other inlet passage, actuating surfaces 95 on the valve intermittently exposed to pressure fluid valved by the piston for throwing the valve, and holding areas on the flange exposed to pressure fluid flowing to the inlet passage for holding the valve in the limiting 100 positions.

5. In a fluid actuated rock drill, the combination of a cylinder and a hammer piston therein, a valve chest having a valve chamber and a supply passage, inlet passages leading from the valve chamber to the cylinder, a valve in the valve chamber having a flange 110 to control the flow of pressure fluid from the supply passage to the inlet passages, control means on the flange for effecting a greater flow of pressure fluid from the supply passage to one inlet passage than to the other inlet passage, heads on the valve 115

of smaller diameter than the flange and having differential pressure surfaces intermittently exposed to pressure fluid valved by the piston for throwing the valve, and holding areas on the flange exposed intermittently to pressure fluid for holding the valve in the limiting 120 positions.

6. In a fluid actuated rock drill, the combination of a cylinder and a hammer piston 130

therein, a valve chest having a valve chamber and a supply passage, pressure chambers in the ends of the valve chamber, inlet passages leading from the valve chamber to the cylinder, a valve in the valve chamber having an intermediate flange to control the flow of pressure fluid from the supply passage to the inlet passages, means on the valve to effect differential areas of communication between the supply passage and the inlet passages, heads on the valve of smaller diameter than the flange and having differential pressure surfaces in the pressure chambers, piston controlled kicker passages for conveying pressure fluid from the cylinder to the pressure chambers to actuate the valve, holding areas on the flange intermittently exposed to pressure fluid for holding the valve in the limiting positions, and vents leading from the kicker passages to the atmosphere to exhaust pressure fluid from the pressure chambers.

In testimony whereof I have signed this specification.
